PERPETUAL CALENDAR RULER

Francis V. Toppin, Lyndhurst, N. J.

Application April 6, 1935, Serial No. 15,036

9 Claims. (Cl. 40—118)

This invention relates to new and useful improvements in a perpetual calendar ruler.

The invention has for an object the construction of a ruler with a mechanism to perpetually give the month, day of the week, and date.

More particularly, the invention contemplates forming the material of the ruler with a cutout area in which the perpetual calendar mechanism is set.

10 A further object of the invention resides in the particular construction of the calendar mechanism for its efficient operation and utility.

The invention contemplates constructing the perpetual calendar in the form of a frame equipped with a cover and supporting several rollers mounted across its ends, and several endless belts mounted between the rollers and printed or inscribed with perpetual calendar data and portions thereof being viewable through window openings in said cover.

20 More particularly, it is proposed to construct the endless belts of elastic so that they firmly engage the rollers and are caused to move if one of the rollers supporting belt is turned.

25 Another object of the invention is the provision of knobs associated with certain of the rollers and extending to exterior by which the calendar may be adjusted.

Another one of the objects of this invention is 30 the provision of a carriage supporting the rollers at one end of the frame and arranged to be adjusted to various positions so that the tension of the elastic belts may be adjusted as desired.

Still further the invention proposes the construction of a device as described which is simple and durable and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

45 Fig. 1 is a plan view of a perpetual calendar ruler constructed according to this invention.

Fig. 2 is an edge elevational view of Fig. 1.

50 Fig. 3 is a perspective view of the perpetual calendar portion of the device with the cover thereof removed.

Fig. 4 is a transverse sectional view taken on the line 4—4 of Fig. 3.

55 Fig. 5 is a fragmentary enlarged sectional view taken on the line 5—5 of Fig. 4.

Fig. 6 is a perspective view of the cover per se.

The perpetual calendar ruler, according to this invention, comprises material 10 in the form of a ruler and having a cut-out area 11 in which a perpetual calendar is set. The ruler 10 has 5 one edge sloping and formed into the ruled edge thereof and imprinted with a scale 12. The perpetual calendar includes a frame 13 having tongues 14 projecting from the ends thereof and engaging in receiving grooves 15 formed in the 10 sides of the openings 11 so that the calendar is supported in position on the ruler.

The perpetual calendar is of smaller width than the size of the opening 11 so that controlling knobs 17 for operating the perpetual calendar, 15 hereinafter further described, may be within the compass of the rear edge of the ruler.

Small blocks 16 are engaged into the free ends of the grooves 15 and are secured in fixed positions by screws 18 and serve to hold the perpetual calendar fixed upon the ruler. It may be removed by first removing the screws and then removing the blocks. The frame 13 is covered by a casing 19. This casing has a top wall 19^a adapted to extend across the top of the frame, 20 a bottom wall 19^b adapted to extend across the bottom of the frame, and an end wall 19^c adapted to extend across the outer side of the frame. This cover is normally held in position with screws 20 engaging through openings in the corners thereof 30 and into threaded openings formed in lugs 21 of the frame.

Three rollers 22, 23 and 24 are rotatively mounted across one end of the frame 13. Another three rollers 25, 26 and 27 are rotatively 35 mounted across the other end of the frame. Three endless belts 28, 29 and 30 are mounted upon the rollers as shown in Fig. 3. More particularly, the endless belt 28 is mounted upon the rollers 22 and 25 and idly extends over the top and bottoms of the rollers 26 and 27. This belt is imprinted or inscribed with the months of the year which may be selectively viewed through a window opening 31 in the casing. The endless belt 29 is mounted between the rollers 23 and 26 40 and idly extends over the rollers 22 and 23. This belt 29 is inscribed with the days of the week which may be selectively viewed through a window opening 31' in the casing 19.

The third belt 30 is mounted between the 50 rollers 24 and 27 and idly extends over the rollers 22 and 23. It is inscribed with numerals indicating the days of the month, which are selectively viewable through window openings 32.

A portion of each roller 22, 23 and 24 is knurled 55

to frictionally engage the endless belts 28, 29 and 30 respectively.

The rollers 22, 23 and 24 extend through the front side of the frame 13 and through openings 5 33 in the end wall 19^a of the cover and at their outer ends are equipped with the knobs 17. The rollers 25, 26 and 27 are mounted upon a pair of strips 35 having tongues 36 engaging in grooves 37 formed upon the inner sides of the center and 10 rear walls of the frame 13. The holding strips 35 consequently are slidable within the frame. A clip 38 is mounted on each strip 35 and has a free end 38' extending through an opening 39 in the holding strip and engageable with notches 37' in 15 the base of the grooves 37 for the purposes of maintaining the holding strips in fixed positions. The bottom wall 19^b of the cover 19 is formed with longitudinal slots 40 disposed immediately below the clips 38 as clearly shown in Fig. 4. The 20 clips 38 are shaped so as to have open areas 41 into which the ends of tools, such as screw drivers, may be engaged.

This arrangement permits a pair of screw drivers to be engaged through the slots 40 into 25 the openings 41 to lift the ends 38 of clips free from the notches 37' and the strips 35 may then be moved forwards or rearwards to adjust the tension of the endless belts 28, 29 and 30. Preferably, these endless belts should be constructed 30 of elastic tapes or similar material. The strips 35 may be latched into new positions merely by the withdrawal of the screw drivers so as to allow the ends 38' of the clips to re-engage the slots in the bases of the grooves 37.

35 The operation of the device is as follows:—The knob 17 on the roller 22 may be turned for adjusting the month indication of the perpetual calendar. The knob 17 upon the roller 23 may be turned for adjusting the day of the week indication of the calendar, while the knob 17 on the roller 24 may be turned for adjusting the day of the month. Preferably, the knobs 17 are of such size that the rims thereof project slightly above the top face of the ruler, as clearly shown in 40 Fig. 2, so that they may be conveniently turned while the ruler lies flat upon a desk. If desired, the knobs may be turned by lifting the ruler so that they may be reached from the rear.

While I have illustrated and described the preferred embodiment of my invention, it is to be understood that I do not limit myself to the precise construction herein disclosed and the right is reserved to all changes and modifications coming within the scope of the invention as defined 55 in the appended claims.

Having thus described my invention, what I claim as new, and desire to secure by United States Letters Patent is:—

1. A perpetual calendar ruler, comprising a 60 ruler, a frame removably mounted thereon, a cover engaging said frame and formed with several window openings, several rollers mounted across each of the ends of said frame, several 65 endless belts mounted between said rollers and printed or inscribed with perpetual calendar data and having portions thereof selectively viewable through said window openings, and means for moving said endless belts.

2. A perpetual calendar ruler, comprising a 70 ruler, a frame removably mounted thereon, a cover engaging said frame and formed with several window openings, several rollers mounted across each of the ends of said frame, several 75 endless belts mounted between said rollers and printed or inscribed with perpetual calendar data

and having portions thereof selectively viewable through said window openings, and means for moving said endless belts, said frame and cover engaging into an opening extended in from the rear edge of the ruler and of a thickness corresponding with the thickness of the ruler. 5

3. A perpetual calendar ruler, comprising a ruler, a frame removably mounted thereon, a cover engaging said frame and formed with several window openings, several rollers mounted 10 across each of the ends of said frame, several endless belts mounted between said rollers and printed or inscribed with perpetual calendar data and having portions thereof selectively viewable through said window openings, and means for 15 moving said endless belts, said frame having tongues on the ends thereof engaging in receiving grooves in the material of the ruler by which the perpetual calendar is mounted in position.

4. A perpetual calendar ruler, comprising a 20 ruler, a frame removably mounted thereon, a cover engaging said frame and formed with several window openings, several rollers mounted 25 across each of the ends of said frame, several endless belts mounted between said rollers and printed or inscribed with perpetual calendar data and having portions thereof selectively viewable through said window openings, and means for 30 moving said endless belts, said frame having tongues on the ends thereof engaging in receiving grooves in the material of the ruler by which the perpetual calendar is mounted in position, and removable blocks mounted upon the ruler for preventing the perpetual calendar from being removed. 35

5. A perpetual calendar ruler, comprising a ruler, a frame removably mounted thereon, a cover engaging said frame and formed with several window openings, several rollers mounted across each of the ends of said frame, several 40 endless belts mounted between said rollers and printed or inscribed with perpetual calendar data and having portions thereof selectively viewable through said window openings, and means for moving said endless belts, said endless belts being present in the numerical number of three, one belt containing the months of the year, the second belt 45 containing the days of the week, and the third belt containing the number of the days in the month. 50

6. A perpetual calendar ruler, comprising a ruler, a frame removably mounted thereon, a cover engaging said frame and formed with several window openings, several pairs of rollers mounted across each of the ends of said frame, one of each pair of rollers being partially knurled, several endless belts mounted between said pairs of rollers so that they engage the corresponding knurled portions of said rollers, and printed or inscribed with perpetual calendar data and having portions thereof selectively viewable through said window openings, and means for moving said endless belts, said endless belts being present in the numerical number of three, one belt containing the months of the year, the second belt containing the days of the week, and the third belt containing the number of the days in the month, comprising knobs connected with certain of said rollers. 60

7. In a perpetual calendar ruler, a frame having parallel sides, a casing encasing said frame and formed with several window openings, a group of rollers at one end of the frame and rotatively mounted thereon and having one of their ends extending through the frame and through the 75

casing to the exterior and equipped with knobs, a second group of rollers located on the other end of the frame and rotative on strips slidably mounted on the inner faces of parallel sides of said frame, several endless belts of elastic material mounted between said rollers and inscribed with perpetual calendar data viewable through said window openings, and means for holding said strips adjusted in various positions and controlling the tension of said belts.

8. In a perpetual calendar ruler, a frame having parallel sides, a casing encasing said frame and formed with several window openings, a group of rollers at one end of the frame and rotatively mounted thereon and having one of their ends extending through the frame and through the casing to the exterior and equipped with knobs, a second group of rollers located on the other end of the frame and rotative on strips slidably mounted on the inner faces of parallel sides of said frame, several endless belts of elastic material mounted between said rollers and inscribed with perpetual calendar data viewable through said window openings, and means for holding said strips adjusted in various positions and controlling the tension of said belts, com-

prising clips mounted upon the strips and engageable with grooves in the frame.

9. In a perpetual calendar ruler, a frame having parallel sides, a casing encasing said frame and formed with several window openings, a group of rollers at one end of the frame and rotatively mounted thereon and having one of their ends extending through the frame and through the casing to the exterior and equipped with knobs, a second group of rollers located on the other end of the frame and rotative on strips slidably mounted on the inner faces of parallel sides of said frame, several endless belts of elastic material mounted between said rollers and inscribed with perpetual calendar data viewable through said window openings, and means for holding said strips adjusted in various positions and controlling the tension of said belts, comprising clips mounted upon the strips and engageable with grooves in the frame, said clips being shaped to have openings in which tools may be engaged, and said cover having longitudinal slots through which said tools may be engaged to reach the clips by which the holding strips may be adjusted.
